UNITED STATES PATENT OFFICE.

CURT J. ROHLAND, OF SEEKONK, MASSACHUSETTS, ASSIGNOR TO NATIONAL COLLAPSIBLE TUBE CO., OF PROVIDENCE, RHODE ISLAND.

MACHINE FOR PLACING CORK DISKS IN CAPS.

Application filed August 6, 1925. Serial No. 48,535.

This invention relates to certain new and useful improvements in a machine for placing cork disks in caps, pertaining more particularly to the caps of collapsible tubes in which are marketed different pastes, the primary object of the invention being to provide an automatic machine for inserting the cork disks in the caps and grooving the latter to receive a retaining wire or hinge loop.

Another object of the invention is to provide a machine in which the proper feeding of the caps and cork disks, which are dumped into respective hoppers, is insured so that the disk may be inserted in the cap.

The invention further resides in the provision of means for ejecting or segregating any improperly positioned caps from the machine.

The invention still further resides in improved mechanism for grooving the skirt of a cap to receive the loop of a hinged cap retaining device.

Another object of the invention is to provide means for transferring a corked cap from the corking mechanism to the grooving mechanism.

Further, the invention is found to reside in the salient features of construction and the arrangements and combination of parts hereinafter described in detail and succinctly set forth in the appended claims, reference being made to the accompanying drawings wherein:

Figure 1 is a top plan view of the machine with portions broken away;

Figure 2 is a side elevation thereof with parts omitted;

Figure 3 is a view similar to Figure 1 but taken at a lower plane and showing the clutch mechanism in section;

Figure 4 is a vertical section on line 4—4 of Fig. 3;

Figure 5 is a fragmentary rear view illustrating the cam shaft and the associated parts;

Figure 6 is a similar view of the front of the machine;

Figure 7 is a horizontal section taken on line 7—7 of Fig. 8, showing the cork inserting mechanism.

Figure 8 is a side elevation thereof showing also the relative position of the gripper jaws and a fragment of the grooving mechanism.

Figure 9 is a similar view showing more clearly the cork and cap chutes;

Figure 10 is a fragmentary view of the cap hopper, depicting the manner in which a cap is ejected from its chute.

Figure 11 is a fragmentary top plan view of the cap hopper and

Figure 12 and Figure 13 are detailed cross-sectional views of the two chutes on lines 12—12 and 13—13, respectively of Figure 9.

In collapsible tubes containing tooth paste, shaving cream and other bodies of pasty constituency, the inner top surface of the cap is usually screwed down into contact with the discharge orifice or neck of the tube, and to prevent any undesirable action which the acids of the paste may have on the metal of the cap, and also to insure cleanliness, a liner, or washer is inserted in the cap, the liner being preferably of cork or fiber. Means are also provided for preventing loss of the cap by encircling a wire about the cap in a groove formed therein and hinging the wire to the body of the tube.

It is the aim of this invention to provide a machine which will automatically perform the corking and grooving operation on the cap.

Referring more in detail to the drawings, the numeral 1 designates the cap hopper having therein an intermittently rotatable, agitator 2 of dome-shape and defining therewith an annular channel 3 which is closed by the bottom 4 of the hopper except for a discharge opening 5 from which leads a magazine chute 6. The agitator 2 is fixed on the upper end of a vertical shaft 7 journaled in the bearing 8 of the frame 9, and on the lower end of the shaft is fixed a large bevel gear 10 and a spur gear 11. The bevel gear 10 meshes with a bevel gear 12 fixed on one end of a horizontally disposed shaft, the opposite end of the latter carrying a ratchet 13 which is given intermittent rotary movement by the pawl 14. The pawl is oscillated from the shaft 15 through the intermediary of a cam on the shaft and the link 16.

A cork hopper 17 is mounted adjacent the cap hopper and likewise has an agitator which is intermittently operated from the shaft 7 by means of gears 11, 18 and 19, the latter being fixed on the shaft 30 of the

agitator. The little cork disks which are to be inserted inside of the caps are delivered from the hopper 17 to a positioning or transfer slide 21 by means of a magazine 5 chute 22, the latter terminating adjacent the lower end of the chute 6.

The slide 21 is provided with a pocket 23 for receiving the cork disks singly from the chute 22 and positioning the same opposite 10 the open end of the lowermost one of the caps 24 in chute 6 for being pushed or pressed thereinto by the plunger 25 which is slidably mounted in the guide opening 26 provided in the slide 21 axially of the pocket 15 23. The inserting pin 25 is held in retracted position by a spring 27 in which position the outer end of the pin normally engages one end of a lever 28, the opposite 20 end of said lever being disposed to engage stop arm 29. Lever 28 is pivoted at 30 on a main slide 31 which also carries the slide 21 and spring 27. The main slide is disposed at a lower level than slide 21 and is provided 25 with a pocket 32 for sliding beneath the lower end of chute 6 to receive the corklined cap therefrom and carry the same to a point beneath a pair of gripping jaws 33. The main slide 31 has a base 34 which is guided for horizontal movement in the frame, such 30 horizontal movement being imparted thereto by a rocker-lever 35. This lever is pivotally mounted in the frame, as at 36, and has its upper end bifurcated to straddle a cross pin 37 in the base 34 said upper end operating 35 in the slot 38 in said base.

This lever arm is rocked by a cam 39 on shaft 15, through a follower lever 40 and a connecting link 41.

The lined cap is removed from its pocket 40 32 by the gripping jaws 33 which descend into the pocket and yieldably close upon the cap by reason of the spring 42 acting outwardly on the ends of the jaws on the opposite side of their pivots 43. These pivots 45 mount the jaws on a carrier 44 which is slidably mounted for vertical movement in a guide 45. A lever 46 is fulcrumed at 47 on a bracket 48 of the frame, the outer end of said lever carrying an upwardly yieldable tip 49 which is pivotally connected thereto, at 50, and adjustable relatively thereto by a set screw 51; the outer end of said yieldable section 49 being slotted to receive the pin 52 projecting laterally from 55 the carrier 44, thereby providing a play connection. A follower roller 53 rides on cam 54 of shaft 15 for imparting vertical reciprocation to the carrier 44. The pocket 32 has its bottom formed with spaced slots 60 55 to permit the jaws 33 to properly pass about the cap which is supported in the pocket between the slots.

After the jaws 33 lift the lined or corked cap from pocket 32, the slide 31 is withdrawn 65 to receive another cap from chute 6

and the carrier 44 is lowered, guided by a pair of coiled springs 56 which connect the cap plate 57 of the carrier to a fixed anchor 58 on the frame, to a position opposite chuck 59, this chuck being journaled in the frame 70 of the machine and provided with a pulley 60 to which power may be applied for rotating said chuck. The cap is pushed out of the jaws 33 into the chuck 59 by a spindle or pusher pin 61 which is yieldably 75 mounted in a support 62, the latter being slidably guided in the bearing 63. The pusher pin is urged forwardly by a pair of coiled springs 64 anchored respectively to the frame and the outer end of the pin, the latter being retracted by means of a lever 65 pivoted at 66 to the frame and acted upon by cam 67 on shaft 15. The active end of this lever is provided with a yieldable forked tip 68 pivoted thereto and adjustable by 80 a set screw 69 to properly adjust the fork 70 which straddles the opposite protruding end of pin 71. The pusher pin 61 is yieldably backed in its support 62 by a coiled spring 72. In its operative position, the 85 pin 61 is steadied by a guide 73.

Following the placement of the cap, in the chuck, the skirt of the cap is grooved exteriorly to receive the bail or loop of a retaining wire. This operation is performed 90 by a pair of cutting bars 74 and 75 the latter being mounted in a holder 76 on a slideable carrier 77 which is provided with a follower roller 78 journaled in a bracket 79, the latter being adjustable on the carrier 100 by a jam screw 80 and a set screw 81 whereby the position of follower 78 may be adjusted relative to its actuating cam 82 on shaft 15. Set screw 83 engages the opposite sides of the rear end of cutter bar 75 to 105 steady the same in its adjusted position. The carrier 77 is slideable between spaced guides 84 and is held in retracted position by coil spring 85. The cutting or grooving bar 74 is mounted in a carrier 86 slidably 110 mounted in the frame and is reciprocated to and from operative position by lever 87 which has its upper forked end engaging a lateral pin 88 on the slide 86, the lower end of the lever 87 being connected by link 89 115 to an actuating lever 90 which, in turn, is pivoted on the frame 91 and has an adjustable tip 92 engaging and following cam 93 on shaft 15.

After the cap has been grooved and the 120 grooving bars 74 and 75 retracted from the pusher pin 61, which also serves as a spindle or journal support for the cap while being rotated by the chuck, is also retracted and the cap is then ejected from the chuck 125 by a pin 94 which is yieldably urged forwardly by a coiled spring 95 the tension of which is momentarily increased by compressing tubular housing 96, the latter being 130 slidable within the chuck body against the

tension of a heavier spring 97. The compressing movement of the housing 96 is effected by cam 98 on shaft 15, which act upon one end of a lever 99 pivoted at 100 to the frame the opposite end of the lever having an adjustable or yieldable, forked tip 101 straddling a collar 102 for reciprocating the housing without restricting its rotary movement.

10 In operation, the caps are dumped into hopper 1 and the liner disks of cork, paper or the like, are dumped into the smaller hopper 17. The machine is then set in motion thereby intermittently moving the agitators 2 and 18 in the respective hoppers, from the spheroidal surfaces of which the caps and disks slide into the respective grooves 3 and 103, resting on their edges or peripheries. The liner disks will be

15 rolled about the groove 103 on their peripheries until they drop into the chute 22, the guide way of which is overhung by a retainer plate 104, as depicted in Figure 9 and Figure 13. The caps are likewise

20 rolled about on their peripheries in channel 3 until they fall into the discharge opening 5 leading to chute 6. In this connection it will be observed that the guideway of chute 6 is substantially T-shape, or con-

25 forms to the shape of the cap. The caps will therefore be guided and held in proper position as they descend the chute, with their open or skirted ends outwardly. Should a cap enter the chute with its closed

30 or head end out it will be deflected by reason of the deflecting guide ways 105 being cut in the opposing walls of the stem portion of the T-shaped guide way. These "detecting" guide ways 105 will receive the

35 heads of wrongly positioned caps and deflect them out of the chute as indicated at 106, Figure 10. It is also possible that the caps might jam in the channel 3 and to overcome injurious effects therefrom the

40 finger 107, which propels the caps around said channel, is pivoted at 108 in the agitating dome 2 and yieldably pressed out into the channel by spring 109 which permits the propelling finger to pass by a jam

45 of caps in safety.

50 With the compound slide 21 and 31 in retracted position a previously lined cap will drop into the pocket 32 and the lowermost liner disk 110 will drop into pocket 55 23 after which the compound slide will be shifted from the position in Figure 9 to that of Figures 7 and 8 which places the liner opposite the lower-most cap in chute 6, which cap is held from lower descent by the upper surface of slide 31 passing therebeneath. As the compound slide ap-

60 proaches its limit of movement the lever 28 engages stop 29 and, by reason of the cam shape of the engaged ends of said lever 28, the liner-inserting pin 25 is

quickly moved inwardly to press the liner disk into the skirted end of the cap. The previously lined cap, now in the extended pocket 32, is grasped by the jaws 33 for subsequent lowering after the retraction of 70 the compound slide. The lowering of carrier 44 positions the cap in jaws 33, opposite the chuck 59 into which latter the cap is inserted by the pusher pin 61, said pusher pin remaining in this position to act as a 75 journal support or bearing while the grooving tools 74 and 75 co-act upon the skirted portion of the cap.

This operation having been accomplished the parts 61, 74 and 75 are retracted and the 80 tension of spring 95 is increased by cam 98 to expel the finished cap from the chuck into a suitable receptacle, not shown.

It will thus be observed that the complete 85 cap-lining operation is performed automatically and without requiring the constant attention of an operator, the caps and disks being dumped promiscuously into their respective hoppers from which they are fed in proper position for subsequent corelation, the improperly placed caps being ejected into a suitable receptacle, not shown, for again being dumped into the hopper.

Having thus described my invention what I claim as new and desire to secure by Letters Patent is:—

1. In a machine of the class described, means for inserting a liner disk in a cap, means for grooving the cap, and means for transferring the lined cap from the first 100 means to the second means, said transfer means comprising cap gripping elements, a carrier supporting the elements, and means for moving the carrier from a position for gripping the cap in said first means and delivering the same to be received by said second means.

2. In a machine of the class described, a cap feeding means, liner feeding means, means for taking a liner from the second 110 means and positioning the same opposite the open end of a cap in the first means, means for pushing the liner from the positioning means into the cap, means for removing the lined cap, and means for grooving the cap removed.

3. In a machine of the class described, mechanism for lining a cap, mechanism for grooving a cap, a transfer carrier movable from a position adjacent the lining mechanism to a position adjacent the grooving mechanism, and means for entering the cap in the transfer carrier and moving it to the grooving mechanism, said means remaining 120 in the cap while being grooved to serve as a spindle bearing therefor.

4. In a machine of the class described, mechanism for lining a cap, mechanism for grooving a cap, a transfer carrier movable from a position adjacent the lining mecha-

nism to a position adjacent the grooving mechanism means for entering the cap in the transfer carrier and moving it to the grooving mechanism said means remaining in the cap while being grooved to serve as a spindle bearing therefor, and oppositely disposed grooving tools movable into contact with diametrically opposite points of the cap.

10. 5. In a machine of the class described, mechanism, for lining a cap, mechanism for grooving a cap, a transfer carrier movable from a position adjacent the lining mechanism to a position adjacent the grooving mechanism, means for entering the cap in the transfer carrier and moving it to the grooving mechanism said means remaining in the cap while being grooved to serve as a spindle bearing therefor, and oppositely disposed grooving tools movable into contact with diametrically opposite points of the cap, and means for ejecting the grooved cap from the grooving mechanism.

6. In a machine of the class described, 25 a cap hopper, a liner hopper, an agitator in each hopper, a chute leading from each hopper for feeding the elements therefrom means for intermittently rotating the agitator and means for inserting a liner into 30 a cap.

7. In a machine of the class described, a cap hopper, a liner hopper, an agitator in each hopper, a chute leading from each hopper for feeding the elements therefrom, 35 a slide having a pocket for receiving a liner element from the liner chute and positioning it opposite the open end of the cap, and a pusher pin slidable in the slide for ejecting the liner element from the pocket and pushing 40 it into the cap.

8. In a machine of the class described, a cap hopper, a liner hopper, an agitator in each hopper, a chute leading from each hopper for feeding the elements therefrom a 45 slide having a pocket for receiving a liner element from the liner chute and positioning it opposite the open end of the cap, a pusher pin slidable in the slide for ejecting the liner element from the pocket and pushing it into 50 the cap, and means operable by and during movement of the slide for operating the pusher pin.

9. In a machine of the class described, 55 a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slid- 60 able in the slide for ejecting the liner element from the pocket and pushing it into the cap, means operable by and during movement of the slide for operating the pusher pin, a second slide having a pocket 65

for receiving the lined cap, said second slide pocket having spaced bottom-openings between which the cap is supported and a pair of jaws movable into the second slide pocket, as permitted by the bottom-opening receiving the tips of the jaws for grasping the cap therein.

10. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slidable in the slide for ejecting the liner element from the pocket and pushing it into the cap, means operable by and during movement of the slides for operating the pusher pin, a second slide having a pocket for receiving the lined cap, a chuck, 75 means for removing the cap from the second slide pocket and positioning it opposite the chuck means for positioning the cap in the chuck and means operating on the cap in the chuck.

11. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap a pusher pin slidable in the slide for ejecting the liner element from the pocket and pushing it into the cap, means operable by and during movement of the slide for operating the pusher pin, a second slide having a pocket for receiving the lined cap, a chuck, 80 means for removing the cap from the second slide pocket and positioning it opposite the chuck means for positioning the cap in the chuck and means operating on the cap in the chuck.

12. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slidable in the slide for ejecting the liner element from the pocket and pushing it into the cap, means operable by and during movement of the slide for operating the pusher pin, a second slide having a pocket for receiving the lined cap, a chuck, 95 means for removing the cap from the second slide pocket and positioning it opposite the chuck, a bearing spindle movable axially of the chuck for pushing the cap from the cap removing means into the chuck, and means for operating on the cap in the chuck.

13. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slidable in the slide for ejecting the liner element from the pocket and pushing it into the cap means operable by and during movement of the slide for operating the pusher pin, a second slide having a pocket for receiving the lined cap, a chuck, means for removing the cap from the second slide pocket and positioning it opposite the chuck, a bearing spindle movable axially of the chuck for pushing the cap from the cap removing means into the chuck, said spindle aiding the chuck in supporting the cap therein, and means operating on the exterior of the cap to groove the same, and means for ejecting the cap from the chuck after the grooving means and the spindle have been moved to inoperative position, said ejecting means comprising a normal spring tensioned cap-engaging pin, and means for increasing the spring tension on the pin.

14. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher slidable in the slide for ejecting the liner element from the pocket and pushing it into the cap, means operable by and during movement of the slide for operating the pusher pin, a second slide having a pocket for receiving the lined cap, a chuck, means for removing the cap from the second slide pocket and positioning it opposite the chuck, a bearing spindle movable axially of the chuck for pushing the cap from the cap removing means into the chuck, said spindle aiding the chuck in supporting the cap therein, means operating on the exterior of the cap to groove the same, and means for ejecting the cap from the chuck after the grooving means and the spindle have been moved to inoperative position.

15. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slidable in the slide for ejecting the liner

element from the pocket and pushing it into the cap, means operable by and during movement of the slide for operating the pusher pin, a second slide having a pocket for receiving the lined cap, a chuck, means for removing the cap from the second slide pocket and positioning it opposite the chuck, a bearing spindle movable axially of the chuck for pushing the cap from the cap removing means into the chuck, said spindle aiding the chuck in supporting the cap therein, means operating on the exterior of the cap to groove the same, and means for ejecting the cap from the chuck after the grooving means and the spindle have been moved to inoperative position, said ejecting means comprising a normal spring tensioned cap-engaging pin, and means for increasing the spring tension on the pin.

16. In a machine of the class described, a cap hopper, a liner hopper, an agitator in each hopper, a chute leading from each hopper for feeding the elements therefrom, a slide having a pocket for receiving a liner element from the liner chute and positioning it opposite the open end of the cap, a pusher pin slidable in the slide for ejecting the liner element from the pocket and pushing it into the cap, means operable by and during movement of the slide for operating the pusher pin, a second slide having a pocket for receiving the lined cap, a chuck, means for removing the cap from the second slide pocket and positioning it opposite the chuck, a bearing spindle movable axially of the chuck for pushing the cap from the cap removing means into the chuck, said spindle aiding the chuck in supporting the cap therein, means operating on the exterior of the cap to groove the same, means for ejecting the cap from the chuck after the grooving means and the spindle have been moved to inoperative position, said ejecting means comprising a normal spring-tensioned cap-engaging pin, means for increasing the spring tension of the pin, and a common operating means for the agitators, the slides, the cap-removing means, the spindle, the chuck and the spring-tensioning means.

In testimony whereof I have signed my name to this specification.

CURT J. ROHLAND.
